ROLLER RING MILL

Siegfried Schauer, Hohenecken, Pfalz, and Ottmar Bacharach, Kaiserslautern, Pfalz, Germany, assignors to Gebr. Pfeiffer Barbarossa-Werke AG., Kaiserslautern, Pfalz, Germany

Filed July 16, 1962, Ser. No. 209,950

Claims priority, application Germany, July 19, 1961, P 18,549; June 29, 1962, P 20,144
4 Claims. (Cl. 241—117)

The present invention relates to mills, particularly roller ring or roller drum mills, and more especially the shape of the housing and of the pressure ring for such mills or equivalent structures. A mill of the type to which the invention is applicable is described in U.S. Patent No. 3,061,208.

In mills of this type a grinding drum rotates in a housing about a vertical axis. The ground material is whirled about and carried along by an air stream which sweeps through the housing. Heretofore the milling elements circulating about the vertical central axis as well as the circulating air stream made it a requisite to construct the housing with a circular cross section, i.e. cylindrically, conically or the like. In such a housing with a curved surface necessarily the design of lateral passages, control apertures, seals, the arrangement of the internal components, particularly the yoke for mounting the wear or friction plates which serve for guiding the pressure ring, etc., involves enormous difficulties.

Accordingly it is proposed in accordance with the invention to construct the housing of mills of this type or of similar structures no longer circular but in the form of a multi-cornered prism which is symmetric with respect to the center axis, and it has been found in practice that the most advantageous form is one of hexagonal cross section.

The angular construction of the housing provides for flat housing surfaces in which the necessary apertures for passages and other components can be accommodated without difficulties.

Moreover, the angular design of the mill provides a surprising advantage as far as the function of the mill or grinder is concerned. The housing of mills of this type connects at the top with a hood in which a sifter is installed. Circumferentially of the grinding drum a ring of nozzles is arranged through which air is blown in. The air space carries a stream of material upwardly from the roller drum to the sifter, which contains a quantity of incompletely ground material which is several times as great as the quantity of the finished product. The work of the sifter is therefore considerably more difficult. The angular construction of the housing by way of the corners provides for a pre-separation of the incompletely ground coarse grain from the material carried upwardly by the air current. Thus the resulting pre-separation provides for easing the load on the sifter. As far as the technical problem posed by the air is concerned, a considerable saving of power is obtained.

Furthermore, the improvement of the control or guidance of the pressure ring made possible by the angular design is of particular importance.

In mills of this type the pressure ring must be guided in the housing, and conventionally that is effected by three rather strong yokes to which the wear plates which are engaged by the pressure ring are secured. The efficiency of the transmission of the moments by way of these yokes to the housing of the mill is quite poor, so that the housing which is conventionally of circular cylindrical form is subjected to considerable forces which result at least in temporary distortions of the housing. Moreover, the mounting of the wear plates is cumbersome, and rapid replacement or exchanging thereof is not possible.

2

In the angular housing in accordance with the invention the wear plates can be arranged in the stiff corner regions of the housing directly on the inner wall, while the pressure ring is provided with guiding members which cooperate directly with the wear plates. Preferably these guiding members and the pressure ring can be in the form of a unitary structure. Further advantages and objects of the invention will become apparent from an embodiment of the invention which is schematically illustrated

in the accompanying drawings that show the mill housing which is preferably of hexagonal cross section wherein the wear disks or plates are provided in three corners of the hexagonal housing which are symmetrically disposed relative to one another. In the drawing:

FIG. 1 is a perspective view of the mill;

FIG. 1a is a section through the mill shown in FIG. 1 taken along line IV—IV in FIG. 3;

FIG. 2 is a horizontal section through the mill housing taken approximately along the line II—II in FIG. 1;

FIG. 3 shows the top view of the pressure ring and of the adjacent components of the mill, and

FIG. 4 is a section taken along the line IV—IV in FIG. 3.

The mill or grinder illustrated is of the roller ring or drum roller mill type. The grinding rollers 1 run upon a roller drum or grinding plate 1a which rotates about the vertical center axis while the plate 1a is rotated in the conventional manner. Circumferentially of the grinding plate a nozzle ring (not illustrated) for blowing in air is provided. The stream of air is indicated by arrows 2 in the housing and moves upwardly with the ground material which it picks up and carries along. The mill is closed at the top by means of a hood 10 in which a sifter or separating screen 10a is provided, which takes care of the separating of the completely ground material that is to be discharged out of the upwardly guided mixture of air, coarsely ground and finely ground material.

The housing of the mill has numerous apertures such as entrance gates, passage apertures, material feed openings and the like which have to be well sealed. In addition a series of built in components is needed, such as supporting means for the roller ring, etc., which partly must be passed through and out of the housing. In this connection the guiding of the pressure ring is of particular significance. As required by the symmetry of rotation of the grinding mechanism, the housings of such mills were heretofore constructed in the form of rotational bodies conforming to the symmetry of rotation, such as conventional cylinders having a circular cross section or the like.

Contrary to this form of construction, the housing in accordance with the invention is constructed as a prism that is symmetric with respect to the vertical center axis. In the embodiment illustrated the mill housing 3 is of hexagonal cross section. Thus it has six plane wall portions 4 which abut in six corners 5. It is possible without structural complications to provide in these plane wall portions gates 6, coverings 7 for the roller ring supports and the like. The housing 3 extends downwardly to a base 8 which is likewise of hexagonal form, and upwardly by way of a flange 9 it merges with an intermediate member 9 which continues on into a round hood 10 for the sifter. Owing to the shape of the housing 3 the intermediate member 9 presents also plane surfaces so that the apertures necessary there may likewise be of structurally simple form, for example, for the material entrance 11.

In FIGS. 1 and 2 there is also shown a drive means 12 for the roller drum or grinding plate 1a and a drive means 13 for the sifter.

In the conventional round mill housings in accordance

with the prior art, the supporting of the pressure ring 14 (FIG. 3) had to be accomplished by way of strong yokes, which in turn were secured to the inner wall of the housing. Conventionally these yokes which formed the corners of an imaginary equilateral triangle were equally distributed circumferentially of the housing of the mill at the level of the pressure ring 14. These yokes then carried the wear plates by means of which the pressure ring 14 was guided.

Similar construction could, of course, also be provided in mill housings of angular cross section. It has been found, however, that a much simpler and better form can be obtained if the advantages provided by an angular mill housing are utilized. In accordance with the invention the said yokes can be eliminated. Merely wear plates 15 are provided in the regions of corners 5 or in a chosen number of them in the mill housing 3 directly upon the inner wall thereof. In the chosen embodiment such wear plates 15 are arranged along three corners 5 of the hexagonal mill housing 3 at the level of the pressure ring 14. Guide members 16 are provided on the pressure ring 14 which can be readily adapted thereto by way of which the pressure ring 14 is guided on the wear plates 15. The pressure ring 14 together with these guide members 16 is preferably made as a unitary structure.

In addition to the very extensive simplification of the structural details afforded by the angular construction of the housing, substantially enhanced effects are obtained for the operation of the mill. As already mentioned, the material introduced and to be worked in the mill is guided upwardly by a circulating air current to the sifter 10a, and in the round housing the proportion of incompletely ground material greatly exceeded the proportion of the finished product that had to be separated by the sifter, so that the operation of the sifter and of the feeding by means of the air stream involved considerable power consumption. With the angular, for example, hexagonal construction of the housing the coarse product carried along in the air current is separated to a large extent in the corners of the housing and returns again to the grinding drum, while in practice only the finely ground material reaches the sifter at the top. Thus a substantial advantage is obtained with respect to the mechanical operating techniques, which is combined with an equally substantial saving in power as far as the air operating techniques of the mill operation are concerned.

Furthermore, the embodiment in accordance with the invention affords that the housing, which provides inherently more resistance against bending factors or other damage than a round cylinder, is only stressed along its stiffest areas such as the corner regions due to the guidance of the pressure ring. Furthermore, the arrangement and the exchanging of the wear plates provide no difficulties whatsoever and may be effected very rapidly. Finally, the conventional strong support yokes which were heretofore required can be eliminated.

It is understood, of course, that if it should appear to be necessary for any reason whatsoever, that the pressure ring can also be supported in all corners of the hexagonal mill housing. Finally the same support is also possible in angular housings of different cross section than hexagonal, while again the supporting may be obtained at all corners or in a selected or predetermined number of corners.

Having now described our invention with reference to the embodiment illustrated in the drawings, we do

not wish to be limited thereto, but what we desire to be protected by Letters Patent of the United States of America is set forth in the appended claims.

We claim:

1. A roller mill of the type having a housing, a grinding plate disposed in said housing for rotation about a vertical axis, roller supporting means, rotatable milling or grinding elements, particularly rollers rotatably supported over said grinding plate by said supporting means, and a sifting device disposed in said housing above said grinding elements, said housing being in the form of a multi-angular prism disposed symmetrically with respect to said vertical axis and defining angular corners providing support laterally of said supporting means.

2. A roller mill of the type having a housing, a grinding plate disposed in said housing for rotation about a vertical axis, roller supporting means, rotatable milling or grinding elements, particularly rollers rotatably supported over said grinding plate by said supporting means, and a sifting device disposed in said housing above said grinding elements, said housing being in the form of a hexagonal prism disposed symmetrically with respect to said vertical axis and said roller supporting means having configurations in supporting engagement with adjacent sides of said prism.

3. A roller mill of the type having a housing, a grinding plate disposed in said housing for rotation about a vertical axis, roller supporting means, rotatable milling or grinding elements, particularly rollers rotatably supported over said grinding plate by said supporting means, and a sifting device disposed in said housing above said grinding elements, said housing being in the form of a multi-angular prism disposed symmetrically with respect to said vertical axis and defining angular corners, said roller supporting means comprising a pressure ring disposed above said rollers, said housing supporting a plurality of wear resistant plates adjacent a plurality of said angular corners and said ring having radially extending guide members forming unitary structure with said ring and being slidable on said wear plates.

4. A roller mill of the type having a housing, a grinding plate disposed in said housing for rotation about a vertical axis, roller supporting means, rotatable milling or grinding elements, particularly rollers rotatably supported over said grinding plate by said supporting means, and a sifting device disposed in said housing above said grinding elements, said housing being in the form of a multi-angular prism disposed symmetrically with respect to said vertical axis and defining angular corners, said roller supporting means comprising a pressure ring disposed above said rollers, said housing supporting a plurality of wear resistant plates adjacent a plurality of said angular corners and said ring having radially extending guide members forming a unitary structure with said ring and being slidable on said wear plates in the direction of said vertical axis.
